**ELECTROMAGNETICALLY OPERATED PAPER
TAPE CODING PUNCH WITH LUBRICAT-
ING MEANS**

John Paul Jones, Jr., Wynnewood, Pa., assignor to Navi-
gation Computer Corporation, Norristown, Pa., a cor-
poration of Pennsylvania

Filed Feb. 18, 1963, Ser. No. 259,151
4 Claims. (Cl. 234—108)

This invention relates to paper tape punches and more
specifically to electromagnetically operated coding
punches.

Many presently used punches are quite complex in
construction and require precision parts. This adds further
complications in accessibility of parts, assembly costs and
maintenance.

Amongst the deficiencies in operating conventional
paper tape punches are the requirements of complex ad-
justment of linkages, the necessity to provide spring op-
erated retraction mechanisms which require considerable
operating power to overcome on the punching cycle, the
disposition of chad, and the need for frequent lubrication
of the punch pins.

It is therefore a general object of the invention to pro-
duce an improved punch which corrects many deficiencies
found in prior art punches.

An auxiliary object of the invention is to provide a
punch which is inexpensive to manufacture and which is
easily maintained.

Another object of the invention is to provide a punch
mechanism which does not require adjustment of linkages.

In accordance with the invention therefore, a solenoid
operated coding punch is provided which requires no
more than three moving parts for each punch. Thus a
solenoid drives a punch pin by way of an intermediate
pivoted lever arm. A novel coupler between the lever
arm and punch pin provides both driving and retraction
action to the punch pin, yet requires no adjustment or
springs and permits easy replacement of pins if required.
Other features include a self-lubricating action, simple
chad removal and a minimum of simply manufactured
parts.

Other objects and features of the invention will be evi-
dent from the detailed description made hereinafter with
reference to the accompanying drawing, wherein:

FIGURE 1 is a plan view, partly in section of a punch
assembly constructed in accordance with the invention;

FIGURE 2 is a perspective view of a portion of a punch
assembly as used in coding paper tape, and

FIGURE 3 is an assembly view of a multiple pin punch
constructed in accordance with the invention.

As shown in FIGURE 1, a punch pin 6 is driven through
a paper tape 7 and die block 16 by action of the pivot arm
8 to produce the chad 9. Punch block 10 holds the slid-
ably mounted punch pin 6 in guide holes and has an oil
wick 11 extending therethrough transversely with the
guide holes. The wick 11 envelopes a portion of the
punch pins 6 for lubrication. The punch pin 6 has a
flattened head 22 with a lower rim for receiving a finger
grasp end of the pivot arm 8. The stroke of the punch pin
6 provided by the pivot arm 8 about pivot pin 13 is long
enough to carry lubrication from the wick 11 into the
punch block pin bearing surfaces 12 and 14. In this manner
the retracted punch pin 11 will have its cutting edge
15 lubricated for each punch cycle by the residue of oil in
bearing surface 14. This produces simply a continuous
long term lubrication of the critical wear surfaces.

A die block 16 has a vertical set of die holes extending
partially therein for receiving the cutting edge of the
punch pins 6. A chad chute 17 is formed through the
die block 16 transversely to the set of die holes and com-

2

municating therewith to permit chad 9 to be dispensed by
gravity action.

Note that construction of each part is simple. In the
die block 16 for example, as may be seen in perspective in
FIGURE 2, a drilled hole through the block for the chad
chute 17, and drilled holes 19 for the pin die into the
chad chute 17 are quite readily made without complex
jigs or unusual manufacturing techniques. In the punch
block similarly the oil wick chute and the pin bearing
holes may be drilled. The pivot arm 8 is a simple stamped
part.

In the punching operation the action of the pivot arm
8 through action of the upper 20 and lower 21 cam sur-
faces serves for both punch and retract operations by en-
gaging pin 6 about the head 22. In the down or punch
stroke, the upper cam surface 20 engages the flat upper
head surface in a roller camming action as it pushes it
into the die block 16 through the paper tape 7. During the
retract operation, the lower cam surface 21 engages the
under rim of the head 22 and forcibly removes the pin
6 from the paper tape 7 and die block 16. This action
precludes the provision of enough force to overcome a
retract spring on the punch stroke and permits fast action
with little power. The cam surfaces are shaped in a finger
grasp configuration to produce a smooth transition be-
tween the punch and retract operations and to avoid ex-
cessive looseness or chatter between the two strokes. The
cam operation basically permits relative lateral movement
between the pivot arm 8 and the pin head 22 surfaces,
rather than a modification of the drive action produced by
the pivot arm moving about pivot pin 13. This sig-
nificantly simplifies the electromechanical linkage used to
drive the punch pins 6.

One of the significant advantages of this drive assembly
is that the alignment of the pin 6 in guide holes of punch
block 10 and the die of die block 16 is not critical as the
angle of the pivot arm changes. Thus vertical pin alignment
is simplified. The pins may be readily replaced
when worn as well as the punch and die blocks.

An overall assembly for eight hole codes is shown in
FIGURE 3, wherein the manner of spacing readily accom-
modates standard telegraphic type specifications of
eight holes across a one inch paper tape. To accomplish
this tight spacing requirement, every other adjacent pin is
longer and mounted at a different level as illustrated by
the alternate pin 26 of FIGURE 1.

The pivot arm 8 is driven by an electromagnetic sole-
noid 29 about pivot pin 13. On each side of the pivot
arm 8 on pin 13 is a nylon bearing washer 30 which
50 serves to hold the pivot arm 8 between the divider
plates 31 and 32 on each side thereof. The mechanical
advantage between the solenoid end of the pivot arm and
the punch drive may be around four to one, for example,
so that a one inch solenoid stroke will produce a one-
quarter inch punch pin stroke.

As seen from adjacent lever arms 8 and 48, the spacing
on two pivot pins 13 and 53 permits the U-shaped divider
32 to hold the lever arms at the different levels shown in
FIGURE 1 to provide a compact assembly that does not
interfere with action of punching eight closely spaced holes
in a one inch paper tape.

In operation, as seen from the perspective view of FIG-
URE 2, the chad chute 17 is mounted vertically to permit
free gravity fall of chad, and to permit the oil wick 11 to
rest in an oil well. Because of the finger grasp end on the
pivot arm 8, the simplified operation directly from the
solenoid is attained with few moving parts and without
critical requirements in alignment, except between the
punch and die blocks which guide the punch pins.

It is therefore evident from the foregoing description
that the present invention affords a simplified yet efficient
coding punch assembly useful in providing punched paper

tape, which may be reproduced readily. This improved coding punch with its various features of novelty is defined with particularity in the following claims.

I claim:

1. An electromagnetically operated paper tape coding punch assembly comprising in combination, a solenoid, a lever arm coupled for motion about a pivot point by said solenoid, a round punch pin having a flat head and a cutting edge on opposite ends, a finger grasp end on said lever arm having an upper cam surface for contacting the top of the punch pin head and a lower cam surface for contacting the lower rim of the head to thereby provide both a punch and retract pin action as the solenoid moves the lever arm back and forth, a punch block assembly having guide holes for said punch pin to extend therethrough and having an inner well with an oil wick therein to envelope a portion of said punch pin near said cutting edge to provide lubricant thereto each time it reciprocates through a punch cycle, and a die block placed for receiving the punch pin cutting edge and mounted to receive a paper tape between it and the punch block and having therein a chad chute for receiving chad removed from paper tape during a punching operation.

2. Punch pin lubrication means in a paper punch assembly comprising a punch block with punch pin guide holes, punch pins having a cutting edge extending through the block, a well cut in said punch block transverse to punch pin guide holes, and an oil wick resting in the well enveloping a portion of the punch pins near the cutting edge extending through the guide holes, and a die block mounted adjacent to the punch block to receive the cutting

edges in reciprocatory movement thereby receiving from the punch pin and cutting edge lubricant imported from said wick.

3. A multiple punch assembly comprising a plurality of U-shaped divider plates, a plurality of solenoids, a plurality of punch pins, lever arms coupling each of the solenoids to drive and retract a corresponding one of the punch pins by camming action about two spaced pivot pins, and bearing washers mounted on each pivot pin on both sides of each lever arm, said divider plates mounted between adjacent sets of bearing washers, wherein one set of two adjacent bearing washers is on one pivot pin and the other set is on the other pivot pin.

4. An assembly as defined in claim 3 wherein each two adjacent punch pins are mounted at different levels.
